UNITED STATES PATENT OFFICE.

HENRY VASSAR LAWLEY, OF KENSINGTON, LONDON, ENGLAND.

PRINTING OF PHOTOGRAPHIC FILMS.

1,413,598.

Specification of Letters Patent. Patented Apr. 25, 1922.

Application filed February 11, 1921. Serial No. 444,118.

To all whom it may concern:

Be it known that I, HENRY VASSAR LAWLEY, of Kensington, London, W. 8., England, a British subject, have invented certain new and useful Improvements in the Printing of Photographic Films, of which the following is a specification.

This invention relates to the printing of photographic films chiefly of the classes used for cinematographic purposes, and the object is to provide a novel method and means whereby such printing may be effected in an entirely automatic manner throughout to produce the proper intensity of light according to the varying intensity of the picture or pictures on the film. The invention is distinct from a known method which provides means for sounding an alarm when it is necessary to manually change the printing light and in which an edge of the film is cut away or notched to permit a contact to be made to produce the alarm, the light required being then applied by the operator after inspection of a previously prepared card or chart giving the varying degrees of lighting for the different sections of the film.

Other means used at present which are termed "automatic printers" consist of an intermittently moving disc or drum on which are pegged contacts, for the purpose of automatically switching in a light of predetermined printing power. A notch is placed in the film on or before each section and as each notch passes through, a contact is made and the disc or drum is caused to move on by means of a ratchet for a distance of one point into the next contact. The contacts are inserted in the disc or cylinder by hand according to a card or chart. Each notch in the film actuates electrically a ratchet moving the disc or cylinder one notch.

According to the present invention the use of such card or charts is dispensed with, and the film negative is prepared in such a manner that the particular intensity of light required for different sections of the film will be entirely automatically applied as or before the film is caused to pass through the usual printing gate or other similar device provided in the apparatus, thus enabling the actual printing operation to be performed by unskilled operators.

The invention may be carried out in a number of different ways, but it essentially consists in the provision of electric contacts or means for producing same at one or both

sides or edges of the film, these contacts being spaced along the film at different distances from one or more key contacts and these distances determining which light shall be applied by the closing of one of a number of different circuits according to which contacts are in operation.

The contacts are provided on the film during its initial inspection or "grading" for the determination of the intensity of light required for the different sections and nothing remains for the printing operator to perform in connection with the actual lighting operations.

The invention consists of an improved method for the entirely automatic printing of films and in the improved apparatus whereby said automatic printing may be carried into practical operation, all as set forth in the following specification and particularly as pointed out in the claim.

An embodiment of the invention is illustrated in the accompanying drawings in which:

Fig. 1 is a front elevation showing the general arrangement of a film printing machine with part of the invention, viz: the contact arrangement, applied thereto.

Fig. 2 is an elevation on an enlarged scale showing said contact arrangement.

Fig. 3 is a view of part of a film showing key contact and a lighting contact thereon.

Fig. 4 is a side elevation on a still further enlarged scale showing one of the circuit closers for the lighting circuit.

Fig. 5 is a plan view on a reduced scale showing the whole switch board and a number of circuit closers as illustrated in Fig. 4 thereon, and

Fig. 6 is a diagram illustrating the electric connections and circuits employed.

To refer firstly to Figs. 1 to 3 the former figure shows the front plate *a* of a conventional form of film printing machine, this plate supporting flanged spindles *a*¹ and *a*² for carrying the film reels for unwinding and re-winding respectively. On leaving the upper spindle *a*¹ the film passes under a guide *b*, then through a contact gate *b*¹, hereinafter described, then under a second guide *b*², over a driving sprocket roller *c*, thence under guides *c*¹ and *c*² passing the printing aperture *c*³ behind which is located the electric lamp, thence over another driving sprocket roller *c*⁴ to the rewind spindle *a*².

The contact gate b^1 above referred to and shown more clearly in Fig. 2 taken in conjunction with the conductive contacts d^1 and d^2 attached to the film d (Fig. 3), will now be described.

For each section or picture of the film d in which a change of printing light is to take place, there is provided a key contact d^1 in the form of a conductive clip located 10 at one edge or side of the film and another co-operating conductive contact d^2 either at the same or at the opposite edge or side of the film and at such a determined distance from the key contact as corresponds to the 15 particular degree of light required for the film section in question. In the particular case under consideration a contact d^2 is shown at a point corresponding to that required for a light of No. 8 intensity, and the 20 description in connection will be retained throughout the specification. The said contacts are suitably in the form of small metal clips attached to the film as by placing their 25 ends through certain of the usual perforations d^3 adjacent the edges of the film and bending them flat at the rear.

The film, as above described, is caused to pass through the contact gate b^1 in advance of the printing aperture c^3 and said gate 30 comprises a non-conductive base e carrying bars or rails e^1 divided into a number of insulated sections with intermediate conductive contacts shown as comprising a key contact e^2 and others designated by the 35 numbers 1 to 10 corresponding to the different intensities of light required. The gate is also provided with a hinged cover or door e^3 (shown open in Figure 2 but closed in Figure 1) this door being provided on its 40 upper surface with conductive bars e^4 adapted to coincide with the bars e^1 on the base and spaced apart therefrom, when the door is closed, and coupled together outside by a conductive connection e^5 (Figure 1).

45 Thus, as the film passes through the gate a circuit will be completed through the key contacts d^1 on the film and e^2 on the gate, then through one bar e^4 , connection e^5 , second bar e^4 , film contact d^2 and gate contact 50 "No. 8" (or any other number according to the position of the contact on the film) and thence through a connection f (Figure 1) to the switch board and lighting circuit to be hereinafter described. It will thus be seen 55 that the bars e^4 connected together by the connection e^5 , or either of said bars, form or forms a connecting member which, in the operation of the device, is positioned adjacent to the contacts 1, 2, 3, 4, 5, 6, 7, 8, 9 60 and 10 and e^2 and is spaced apart therefrom, the film d with its contacts d^1 and d^2 being adapted to connect said contacts 1, 2, 3, 4, 5, 6, 7, 8, 9 and 10, or either of them with the key contact e^2 , by means of said connecting 65 member. It will be obvious, as the film

passes through the gate and the contacts cooperate to close the circuit as described, that according to the location of the film contact d^2 relatively to the key contact d^1 the degree of light will be produced which corresponds to that required for properly printing the following section of films.

Should a considerable number or range of lights be required, for instance, more than can be conveniently provided for by the size 75 of the gate, and to avoid undue length of said gate I may arrange the gate contacts to cooperate with the film contacts in such a manner that any particular pair of contacts may serve for two different lights, for 80 instance in practice, one gate contact may serve for lights designated 1 and 6, another for lights 2 and 7, a third for lights 3 and 8 and so on according to the total number of different intensities of light required. 85

The preferred apparatus employed for closing the lamp circuits will now be described, reference being directed to Figs. 4, 5, and 6 of the drawings. As shown in Fig. 5 there is provided, one for each change of 90 light, in the present case ten in number, a tumbler switch each of which comprises a pair of electro-magnets or coils g and g^1 and a pivoted armature g^2 , one end of which is provided with extensions g^3 dipping into 95 mercury cups g^4 and the other end of which is counterbalanced by an adjustable nut g^5 mounted on a screw g^6 which is held against accidental displacement by a light spring g^7 . The armatures g^2 are pivotally mounted 100 by means of pins h in grooves h^1 in a bus-bar h^2 extending between the two series of magnets. Each electro-magnet g is also fitted with a shunt device comprising a spring armature i^1 adapted to be attracted 105 by a pole piece i^2 mounted on the top of the magnet g , the arrangement being such that when the magnet g is energized the armature i^1 is also attracted to short circuit the magnet g^1 corresponding to the pair, for a 110 purpose to be described.

To now refer specifically to Figure 6, it will be seen that the gate key-contact e^2 is connected through the means hereinbefore described to contact "No. 8" and thence 11 through the conductor j to electro-magnet or coil g , which is energized from battery x , through connection n^2 , bus-bar h^2 and connections, attracts its armature g^2 and closes the circuit through the extensions g^3 112 and mercury cups g^4 , thence over the resistance k , through the lamp l , conductor m , battery x , conductor n to other coils g^1 through all of which it passes (with exception of No. 8) by means of series connections 12 n^1 which connect said coils g^1 together to energize same and hold the respective tumbler switches open by reason of the armatures g^2 being held by the coils g^1 in the position illustrated in dotted lines Fig. 4 with 13

the extensions g^3 out of contact with their respective mercury cups g^4 and thence back to key-contact e^2 by way of conductor o .

It will be obvious that the greater the length of the resistance k which the current has to traverse the less intense will be the light produced at lamp l . The holding open of all switches except No. 8 is very necessary to ensure that immediately the light is 10 changed only the coil g for the particular light is energized and any previously closed switches are at once re-opened, thus avoiding any possibility of two switches being closed at the same time.

15 The coil g^1 of No. 8 is short-circuited by the shunt device i^1 i^2 , thus avoiding the energization of this coil and any tendency which might arise in consequence of the switch for the light desired being improperly reopened, and in this case the return 20 circuit, instead of passing through the coil g^1 of No. 8 as mentioned, is shunted by the shunt device through an auxiliary circuit including the conductor p , switch i^1 , (shown 25 closed for No. 8) and conductor r . The circuit of only one pair of coils has been described since the description applies to all the others which are similarly arranged.

The attractive effort of the coils g is sufficient to release the rear end of the armature g^2 from the restraining effect of the light spring g^7 , but on the other hand this spring retains the armature in open-circuit position 30 against vibration or other exterior influences likely to occur.

What I claim as my invention and desire to secure by Letters Patent of the United States is:—

1. A method for the entirely automatic 40 printing of photographic films, which consists in providing the films with conductive contact means, passing said film through a device also provided with contact means adapted to co-operate with those on the film, 45 passing the film past a printing aperture and connecting the contact means of said device with a source of light whereby the intensity of the latter will be increased or reduced according to the co-operation of 50 different contacts on the film and device.

2. A method for the entirely automatic printing of photographic films, which consists in providing the film with a key contact and with a plurality of other contacts 55 at various distances from the key contact according to the intensity of light required for printing different sections of the film, passing the latter through a device provided with contacts adapted to co-operate with 60 those of the film, passing the film past a printing aperture behind which is a source of electric light, and connecting the contacts of said device with said source of light whereby the intensity of the latter will be 65 increased or reduced according to the co-

operation of different contacts on the film and device corresponding to the aforesaid different sections of film.

3. A method for the entirely automatic printing of photographic films, which consists in providing the film with conductive contact means, passing said film through a device also provided with contact means adapted to co-operate with those on the film, 70 passing the film past an illuminated printing aperture, and electrically connecting the contacts of said device to a source of illumination adjacent the printing aperture through apparatus comprising a plurality of switches, one for each pair of co-operating contacts on the film and device whereby the intensity of the illumination will be increased or reduced according to the co-operation 75 of different pairs of contacts on the film and device relating to different sections 80 of the film.

4. Apparatus for the automatic printing of photographic films, comprising a film provided with contacts, a device through which said film is passed and provided with 90 contacts adapted to co-operate with those on the film, a source of light adjacent a printing aperture past which the film is caused to travel, and electrical connections from the contacts of said device to said source of light 95 whereby the intensity of the light is increased or reduced according to the co-operation of different contacts on the film and device respectively.

5. Apparatus for the automatic printing of 100 photographic films comprising a film provided with a key contact and a plurality of other contacts at various distances therefrom for different sections of the film, a device through which said film is passed and 105 provided with contacts adapted to co-operate with those on the film in the passage of the latter through the device, a source of light adjacent a printing aperture past which the film is caused to travel and electrical means connecting the contacts of said 110 device with the source of light and including a resistance more or less of which is utilized to reduce or increase the intensity of the light according to the co-operation of 115 different contacts on the film device corresponding to the aforesaid different sections of film.

6. Apparatus for the automatic printing 120 of photographic films comprising a gate having conductive contacts and through which an associated film also provided with co-operating conductive contacts is adapted to be passed, a source of light adjacent a printing aperture past which the film is 125 traversed, a switch device, circuit connections from the contacts on the gate through said switch device to the source of light and a resistance in said circuit connections between the switch and the source of light. 130

7. Apparatus for the automatic printing of photographic films comprising a gate having conductive contacts and through which an associated film also provided with 5 co-operating conductive contacts is adapted to be passed, a source of light adjacent a printing aperture past which the film is traversed, a switch device comprising a plurality of switches one for each pair of co- 10 operating gate and film contacts, circuit connections from the contacts on the gate through said switch device to the source of light, a resistance in said circuit connections between the switch and the source of light, 15 means for closing the switch which corresponds to a pair of co-operating contacts, and means for holding open all the remaining switches.

8. Apparatus for the automatic printing 20 of photographic films comprising a gate having conductive contacts and through which the film also provided with co-operating conductive contacts is caused to pass, a source of light, a switch device comprising 25 a number of switches, one for each pair of co-operating gate and film contacts, each of said switches comprising a pair of electro- magnets, an armature pivoted centrally thereof and a mercury cup, circuit connec- 30 tions from said gate contacts to each switch,

other circuit connections between the mercury cups of the switches and the source of light and a resistance coupled to each switch in said last mentioned circuit connections.

9. Apparatus for the automatic printing 35 of photographic films comprising a gate having conductive contacts and through which the film also provided with co-operating conductive contacts is caused to pass, a source of light, a switch device comprising 40 a number of switches, one for each pair of co-operating gate and film contacts, each of said switches comprising a pair of electro- magnets, an armature pivoted centrally thereof, and a mercury cup, circuit connec- 45 tions from said gate contacts to each switch, other circuit connections between the mercury cups of the switches and the source of light, a resistance coupled to each switch in said last mentioned circuit connections, and 50 means for short circuiting one electro-magnet of a pair when the switch containing these magnets is closed.

In witness whereof I have signed this specification in the presence of two 55 witnesses.

HENRY VASSAR LAWLEY.
